UNITED STATES PATENT OFFICE.

PINCUS FARB, OF NEWARK, NEW JERSEY, ASSIGNOR TO SONORA PHONOGRAPH CORPORATION, A CORPORATION OF NEW YORK.

FASTENING DEVICE FOR SOUND-BOXES.

1,321,193.

Specification of Letters Patent. Patented Nov. 11, 1919.

Application filed February 1, 1917. Serial No. 145,943.

To all whom it may concern:

Be it known that I, PINCUS FARB, a citizen of the United States, and a resident of the city of Newark, county of Essex, and 5 State of New Jersey, have invented a certain new and useful Improvement in Fastening Devices for Sound-Boxes, of which the following is a specification.

My invention relates to a device for securing the reproducer, commonly called a sound-box, of a talking machine to the tone-arm, and has for its objects to produce a device whereby the reproducer will be securely held to the tone-arm, and at the same time 10 permit of the independent movement of the sound-box and tone-arm transversely to their axes. Such independent movement will permit said box to vibrate freely, and the sound box will not be subject to any 15 shocks or strains due to sudden or abrupt movement of the tone-arm. A further object is to provide means for easily applying the sound-box to the tone-arm, and the ready removal therefrom, and to allow for 20 adjustment of the sound-box relatively to the tone-arm.

A further object is to produce a device which will be simple and inexpensive to manufacture, and effective in operation.

0 I have illustrated my invention in the accompanying drawings, in which like reference characters designate corresponding parts in all of the several figures.

In the drawings,

5 Figure 1 is a plan view of a tone-arm and sound-box embodying my invention;

Fig. 2 is a side elevation of the same; and

Fig. 3 is a section taken on line 3—3 of Fig. 2.

In the drawings, 1 designates the tone-arm which may be constructed of wood, veneering, metal or other suitable material. Carried by the tone-arm 1, is a reproducer 2 having therein a diaphragm 3 and having its inner portion projecting into the tone-arm and spaced from the walls thereof, so as to permit of an independent movement of the reproducer transversely of the axes of the tone-arm and reproducer. To the center of the diaphragm 3 is attached a stylus bar 4 which carries a socket 5, in which there is a stylus 6. The socket 5 has secured to it a

spring 7, extending a short distance on each side of the socket. Said spring is held in contact with the frame of the sound-box by 55 means of screws 8—8.

Attached to and projecting from the tone-arm 1 is a series of spring fingers 9, constructed of spring steel and shaped to engage and fit the periphery of the sound-box 60 and permit of the ready removal and insertion of the sound-box. Preferably, the spring fingers 9 are fixed to and carried by a band 9', and as shown in the drawings, they are secured to the band by means of screws 65 10; or they may be secured thereto in any other suitable manner. The band 9' is fitted in a circumferential groove in the end of the tone-arm and held in place by screws 10'; but, I desire it understood that I do not 70 limit my invention to this particular arrangement, as the spring fingers may be held in place upon the tone-arm by means of a metallic ring sprung over the spring fingers and secured or tightened by a screw or other 75 suitable means, or they may be held in place in any other suitable or desired manner.

Between the sound-box 2 and the end of the tone-arm 1 I preferably place an annular cushion 11 to prevent escape of sound 80 waves and to prevent rattling.

The sound-box can be easily removed from its supporting means by a slight forward movement.

To place the sound-box in the retaining 85 means, it is necessary to insert one side of the box first, and then press the spring 9 slightly outwardly by means of the sound-box.

In accordance with the provisions of the patent statutes, I have described the principle 90 of my invention together with the apparatus which I now consider to represent the best embodiment thereof, but I desire to have it understood that the apparatus shown is merely illustrative, and that the invention 95 can be carried out in other ways.

Having now described my invention, what I claim and desire to secure by Letters Patent is:

1. A fastening device for securing sound-boxes to tone-arms of talking machines, comprising a series of spring fingers fixed to and projecting beyond the end of the tone-arm and adapted to fit and engage the pe-

- peripheral edge of the sound-box, to removably and yieldingly hold said sound-box in place.
2. A fastening device for securing sound-boxes to tone-arms of talking machines, comprising a band fitted upon the end of the tone-arm, a series of spring fingers fixed to and projecting from the end of the tone-arm and adapted to fit and engage the peripheral edge of a sound-box, to removably and yieldingly hold said sound-box in place.
3. A fastening device for securing sound-boxes to tone-arms of talking machines, comprising a series of spring fingers fixed to and projecting beyond the end of the tone-arm and adapted to fit and engage the peripheral edge of a sound-box to removably and yieldingly hold said sound-box in place, said sound-box having a portion projecting into and spaced from the walls of the tone-arm,
- to permit relative movement of the sound-box and tone-arm transversely to the axes thereof.
4. In a device for securing sound-boxes to tone-arms of talking machines, a tone-arm, a sound-box having a portion extending into and spaced from the inner walls of the end of the tone-arm, and means engaging the end of the tone-arm and the peripheral edge of the sound-box to yieldingly hold said sound-box in place, to thereby permit relative movement between said sound-box and tone-arm transversely of the axes thereof.
- This specification signed and witnessed this 10th day of January, 1917.

PINCUS FARB.
